FEED FOR FORMING MACHINES

Leslie W. Barnes, Long Hill, Conn., assignor to
 The Baird Machine Company, Stratford, Conn.,
 a corporation of Connecticut

Application July 19, 1940, Serial No. 346,335

14 Claims. (Cl. 140—130)

This invention relates to a feed for a forming machine, or any other machine requiring a similar feed, and has for an object to provide an improved feed in which the feed grip for advancing the work and the clamp for holding the work on the reverse movement of the feed grip are operated by the same mechanism, with which they are always in controlled relation in all positions of the feed slide, so that retiming of the clamp or of the feed does not throw the feed grip out of synchronism with the clamp, but on adjustment of the feed grip operating means the operation of the clamp automatically remains in time with the feed so that a separate adjustment or timing of the clamp is not necessary.

It is also an object of the invention to provide a construction and arrangement whereby when the feed grip is adjusted the clamp is always maintained in timed relation thereto without further adjustment.

It is a further object of the invention to provide a construction in which there is surplus of motion in operation of the feed grip to grip the work and the clamp to clamp the work so that the feed grip grips the work before the clamp is released and vice versa, and the work is always held by one or the other means so that it cannot shift in relation to the following operations and thus gives more accurate feed.

It is a still further object of the invention to provide an improved throw-out for the operating shaft for the feed gripping means, so that the feed grip does not advance far enough to grip the work, to permit setting-up, adjusting, etc.

With the foregoing and other objects in view I have devised a construction illustrated in the accompanying drawings forming a part of this specification. It is, however, to be understood that I am not limited to the exact construction and arrangement shown, but may employ various changes and modifications within the scope of the invention.

In these drawings:

Fig. 1 is a top plan view of the forming machine showing my improved feed device applied thereto;

Fig. 2 is a front elevation of the feed slide and operating means therefor;

Fig. 3 is an end elevation looking from the left of Fig. 2;

Fig. 4 is a top plan view of the feed grip with parts broken away and the top guide for the movable jaw removed;

Fig. 5 is a transverse section thereof substantially on line 5—5 of Fig. 4;

Fig. 6 is a detail end elevation of a portion of the crank drive and on an enlarged scale, the view being substantially on line 6—6 of Fig. 2;

Fig. 7 is a top plan view of the holding clamp and the operating means therefor;

Fig. 8 is a transverse section thereof substantially on line 8—8 of Fig. 7;

Fig. 9 is a section of the throw-out device substantially on line 9—9 of Fig. 8 and on a larger scale;

Fig. 10 is a section substantially on line 10—10 of Fig. 9;

Fig. 11 is an end view of the eccentric of the throw-out; and

Fig. 12 is a section substantially on line 12—12 of Fig. 7.

Referring first to Fig. 1 the forming machine shown comprises a frame 1 in which the main drive shaft 2 is mounted and is operated by any suitable means, such as pulley 3, from any suitable source of power (not shown). A fly wheel 4 may be mounted on this shaft 2. A pinion 5 on the shaft 2 meshes with the gear 6 on the shaft 7 which through suitable beveled gears 8 and 9 drive longitudinal shafts 10 and 11 respectively. The shaft 10 through beveled gears 12 in turn drive a second transverse shaft 13. On the shaft 7 may be mounted a cam 14 operating suitable forming tool slide 15 through any suitable connection 16. On shaft 10 may be cams 17 and 18 operating other tools through connections 19 and 20 respectively. On shaft 11 may be a cam 21 operating another tool slide 22 through suitable connection 23 and on the shaft 13 may be a cam 24 operating slide 25 through connection 26. A cut off 27 for cutting the work may be provided, and operated by a lever connection 27a from a cam 27b on shaft 11. These slides and connections are not shown in detail as they may be used to operate any suitable forming tools for performing any suitable operations on the work and do not of themselves form any part of my present invention, this invention relating to the feed device for feeding work to these tools.

The work to be fed to the tools to be operated on is shown as a wire 27, but the feed is equally adapted for other shapes of work, such for example as a flat strip or the like. The wire 27 is shown as being advanced from a suitable coil, not shown, through straightening rollers 28 and 29. The means for advancing the work and drawing it through these straightening rollers comprises a feed grip on a feed slide 30 mounted on a suitable dovetail

guide 31 on the frame of the machine. The slide is reciprocated back and forth on the guide by a link 32 connected to a feed rocker arm 33 pivoted at 34 on an arm 35 secured to the frame, the link 32 being pivoted to this arm at 36. The rocker arm 33 is rocked on a pivot 34 by a link 37 pivotally connected at 38 to the arm 35 and at 39 to a crank 40 mounted on the shaft 13 to be operated thereby. The connection 39 to this crank is adjustable toward and from the shaft 13 so as to vary the throw of the crank and thus the movement of the feed slide 30, and adjust the amount or length of wire or other work which is fed forwardly on each forward movement of the feed slide 30. The connection 39 is shown as a headed stud 41 with its head 42 in a T slot 43 in the crank wheel 40, and an adjusting rod 44 threaded to the stud 41 may be rotated to adjust the stud and connection 39 along the slot 43 toward and from the axis of the shaft 13 to thus vary the length of movement of the feed slide. This rod 44 may be operated by any suitable means, such for example as a wrench in a non-circular socket 45 in the head 46 secured to this rod.

The feed grip carried by the slide 30 comprises a stationary jaw 47 and a movable jaw 48 cooperating therewith to grip the work 27 between them. The stationary jaw 47 is backed up by an adjusting screw 49 whereby the position of this jaw may be adjusted, and the jaw is held between portions 50 of the slide. The movable jaw 48 is carried by a block 51 slidable in a guide 52 in the slide, and it is operated to clamp the work between the jaws 47 and 48 by means of a toggle 53 operated by a lever 54 pivoted in the slide 30 by a shaft 55. The toggle link 53 is connected with the lever 54 by a pivot rod 56 and with the block 51 by a similar rod 57. The lever 54 has a laterally projecting arm 58 located with its free end in a groove 59 extending longitudinally of an operating shaft 60. This shaft extends parallel to the path of movement of the feed slide and may be mounted by any suitable means, such as bearings 61, 62 and 63 carried by the frame. The longitudinal groove 59 extends substantially the full length of the shaft, or that is, at least as far as the maximum throw or travel of the feed slide, so that the arm 58 is always in this groove in all positions of the feed slide, and therefore the feed shaft is always in operative relation to the toggle lever. In other words the feed grip is always in controlled relation with the operating shaft, and, as will later be described, as the work holding clamp is also always in controlled relation with the operating shaft the feed grip and the clamp are always in controlled or controlling relation to each other. It is therefore impossible to get the two out of the proper relation to each other.

The clamp to hold the work during reverse movement of the feed grip, and also during the cutting-off operation, is shown more clearly in Figs. 7 and 8. It comprises a stationary jaw 64 the position of which is held by means of a screw 65, and it is held in a vertical groove in a block or member 66 supported against the housing 67. Within this housing is a movable jaw 68 arranged to cooperate with the jaw 64 to clamp the work. The jaw 68 is pivoted at 69 to a slide 70 which is reduced at 71 to pass through a collar 72 threaded in the housing 67. A spring 73 embraces the reduced portion 71 and tends to advance the slide 70 and

the jaw 68 to clamp the work against the jaw 64. Within the slide 70 is an adjustable rod 74 threaded to the slide 70 at 75, and it may be adjusted relative to the slide 70 by rotating this rod by means of a screw driver or the like in the slot 76, and locked in adjusted position by a nut 77. An operating lever 78 pivoted in the housing at 79 has one arm 80 engaging the end of the rod 74 and the end of the other arm 81 in a groove 82 in the operating shaft 60. Rotation of the shaft 60 in a clockwise direction as viewed in Fig. 8 will operate the lever 78 counterclockwise to move the jaw 68 to the left to release the work. Movement of the shaft 60 counterclockwise will permit the spring 73 to advance the jaw 68 to clamp the work.

The operating shaft 60 is operated or oscillated to operate the feed grip 48 and the clamp 68 by means of an internal cam 83 on the shaft 60. This cam has a cam groove 84 in which runs a roller 85 mounted on one arm of a lever 86 pivotally mounted on a shaft 87. Connected with the other arm of the lever 86 is a link 88 pivoted at one end to the lever at 89 and at the other end pivoted to a crank 90 on the operating shaft 60. It will thus be seen that operation of the lever 86 by the cam 83 will operate the shaft 60.

The feed grip jaws and the clamp jaws are so adjusted relative to each other, and the operating means for the feed grip and clamp are also so arranged, that there is a surplus of motion in the feed grip and clamp so that in the operation of the feed grip to grip the work the first part of the motion of the operating shaft 60 clamps the feed grip 48 and the latter part of the continued movement of the shaft releases the clamp 68. On reverse movement of the shaft the first part of this movement clamps the work by the clamp 68, and the latter part of the continued movement of the shaft releases the feed grip 48. Thus the work is always gripped by either the feed grip or the clamp so that it cannot shift in relation to the following operations. This gives a more accurate feed (and also maintains a perfectly accurate feed) and it is secured by a surplus of motion in the feed grip and clamp. Thus, more specifically, when the grooved operating shaft 60 is turned to the left or counterclockwise as viewed in Fig. 5 the first part of this motion operating through the lever 58 and toggle 53 clamps the feed grip 48 against the work and the later part of the continued movement of this shaft releases the clamp 68. Continued movement after clamping of the feed grip is permitted by the toggle connection 53, but of course the actual movement required of the clamping jaw is very small and is exaggerated on the drawings. On the reverse movement of this operating shaft 60 the operation is just the opposite. The first part of this movement releases the lever 78 to permit the spring 73 to shift the jaw 68 to clamp the work, and the latter part of continued movement of the shaft 60 releases the feed grip 48.

In operation rotation of the crank 40, through the connecting link 37, oscillates the rocker arm 33, and oscillation of this arm through the link 32 reciprocates the feed slide 30 and the feed grip comprising the jaws 47-48, the toggle 53 and the operating lever 54 carried by the slide. As the free end of the arm 58 of this operating lever slides in the grooves 59 extending longitudinally in the operating shaft 60 throughout the entire movement of the slide, this operating lever

is in operative and controlled relation with the operating shaft in all positions of the slide.

The work holding clamp 68 is also operated by the operating shaft 60 through the operating lever 78 and its connection to the slide 70.

The operating shaft 60 is operated from the shaft 11 by the cam 83 oscillating the lever 86 which is connected to the shaft 60 by the link 88 connected to the crank 90 on the shaft 60. Therefore the operating shaft 60 is oscillated by a single operative means and the oscillation of the shaft 60 operates both the feed grip 48 on the feed slide and also the work holding clamp 68, and therefore both the feed grip and the holding clamp are operated by a common operating means which is not affected by the operating means for the feed slide. Thus adjustment of this operating means does not change the timing of either the feed grip or the holding clamp relative to each other.

It will be seen from the foregoing description that as the feed grip and the work holding clamp are operated from the same operating means, that is the shaft 60, with which they are always in controlled or controlling relation in all positions of the feed slide and feed grip, the feed grip and the clamp are always in controlled or controlling relation with each other. It is therefore impossible to get the two out of proper relation to each other, and they are always in proper timed relation. Thus in adjusting the feed the clamp automatically stays in time with the feed when the feed clamp or operating crank is adjusted. That is, when the feed grip is adjusted the clamp is automatically taken care of without further adjustment. This is not true where a feed is crank operated and the clamp is operated by a separate means. In such arrangements if an adjustment is made in the position of the crank the timing automatically changes thereby throwing the timing of the clamp out of synchronism with the feed, thus necessitating a retiming of the clamp to synchronize with the feed. With the present arrangement where the crank operated feed and the clamp are operated by the same grip operating means, the clamp automatically stays in time with the feed when the feed operation is adjusted.

The connection at 89 is a manually operable throwout connection which may be operated at will to make the connection from the cam to the shaft 60 ineffective. It is shown in detail in Figs. 9, 10 and 11. Mounted in the forked end 86' of the lever 86 is a short shaft 91, one portion of which 92 is enlarged and has a groove 93 cooperating with the spring-pressed plunger 94 to retain the shaft in position, but permit it to be rotated in the lever arm. The end of this plunger is pressed into the groove by a spring 95, and the friction of the plunger in the groove retains the shaft in the position to which it may be turned by means of a hand lever 96 on a collar 97 secured to the shaft by a pin 98. The shaft includes an eccentric 99 which is embraced by the head 100 of the link connection 88 and forms a pivotal connection between this link and the lever 86. This eccentric is so arranged that when the hand lever 96 is thrown to the position of Figs. 8, 9 and 10 the link connection 88 is thrown forwardly and operation of the lever 86 by the cam 83 will operate the feed grip 48 and clamp 68 in the manner as described. If, however, it should be desired to render the feed grip and clamp ineffective, such for example in setting up the machine, adjusting the tools, etc., which may

require partial operation of the machine without operation of the feed, all that is necessary is to swing the lever 96 to the left a half revolution to the dotted position in Fig. 8. This will swing lever 5 the eccentric 99 through 180° and will shift the link connection 88 in a direction away from the operating shaft 60, and will rock this shaft to the right or clockwise as shown in Fig. 5 sufficiently so that operation of this shaft by the cam 83 while the eccentric 99 is in this position will not advance the feed grip jaw 48 sufficiently to grip the work and will not withdraw the clamping jaw 68 sufficiently to release the work. This will permit operation of the machine to try out the tools, to permit the proper setting, and any other operations desired without operating the work feeding device. Merely throwing the hand lever 96 back to the right to the full line position of Fig. 8 (which is also the position of Figs. 9 10) will again render the feed and clamp release operative. These movements of the hand lever 96 and the eccentric 99 may be determined by a suitable stop means. A convenient stop is secured by extending the end 101 of the pin 98 beyond the collar 97 and providing stop shoulders 102 and 103 at suitable locations in the head 86' on opposite sides of the collar 97 which are engaged by this projecting end 101 to limit the turning movements of the levers 96 and the eccentric 99. The link 88 may include a turn buckle 88' for adjustment of the length of the link connection.

Suitable guides 104 for the work 27 may be carried by the slide 30 to maintain the work in proper position with respect to the jaws 47 and 48. There may also be adjustable stops or abutments to be engaged by the feed slide at opposite ends of its movement to take out back lash at both ends of the stroke of the feed slide.

Having thus set forth the nature of my invention, what I claim is:

1. In a feed for forming machines, a feed slide, means for reciprocating the slide, a feed grip on the slide for gripping the work to feed it forwardly, a clamp to grip the work on reverse movement of the feed grip, a common means for operating both the feed grip and the clamp, and means for operating said common operating means in certain timed relation with operation of the slide.

2. In a feed of the character described, a feed slide, means for reciprocating the slide, an operating shaft parallel with the path of movement of the slide, a feed grip on the slide to grip the work to feed it forwardly, a clamp to grip the work on reverse movement of the feed grip, operating connections from the operating shaft to the feed grip and to the clamp constantly in controlled relation with the shaft, and means for oscillating the shaft in certain timed relation with operation of the slide to operate both the feed grip and the clamp.

3. In a feed of the character described, a feed slide, means for reciprocating the slide, a feed grip on the slide for gripping the work to feed it forwardly, a clamp to grip the work on reverse movement of the feed grip, a common operating means for both the feed grip and the clamp, operating connections from the common operating means to the feed grip and to the clamp constantly in controlled relation with the said operating means, and means for operating the common operating means in certain timed relation with the operation of the slide.

4. In a feed of the character described, a feed

slide, means for reciprocating the slide, an operating shaft parallel with the path of movement of the slide, a feed grip on the slide to feed the work forwardly including a movable jaw, a laterally extending arm on the slide for operating the jaw, said shaft having a groove therein to receive the end of the arm for operating it and extending for the full movement of the slide, a clamp to grip the work on reverse movement of the slide, an operative connection from the shaft to said clamp, and means for operating the shaft in certain timed relation with operation of the slide.

5. In a feed of the character described, a feed slide, means for reciprocating the slide, an operating shaft parallel with the path of movement of the slide, a feed grip on the slide to feed the work forwardly, means on the slide for operating the grip and having sliding engagement with the shaft so constructed that the shaft may operate the grip in all positions of the slide, a clamp to grip the work on reverse movement of the slide, an operative connection from the shaft to the clamp, and means for operating the shaft.

6. In a feed of the character described, a feed slide, means for reciprocating the slide, an operating shaft parallel with the path of movement of the slide, a feed grip on the slide to feed the work forwardly including a movable jaw, a pivoted lever on the slide, a toggle connection from the lever to the jaw, said shaft having a longitudinal groove into which an arm of the lever projects for sliding connection with the shaft, said groove being of a length to give operative connection between the shaft and lever in all positions of the slide, a clamp to grip the work on reverse movement of the slide, an operative connection from the shaft to said clamp, and means for operating the shaft.

7. In a feed of the character described, a feed slide, means for reciprocating the slide, an operating shaft parallel with the path of movement of the slide, a feed grip on the slide to grip the work to feed it forwardly, a clamp to grip the work on reverse movement of the feed grip, an operative connection from the shaft to the feed grip in controlled relation with the shaft in all positions of the slide, an operative connection from the shaft to the clamp, cam means, and means operated by the cam means for oscillating the shaft to operate both the feed grip and the clamp.

8. In a feed of the character described, a feed slide, means for reciprocating the slide including a crank, means for adjusting the length of the crank, an oscillatable operating shaft parallel to the path of movement of the slide, a feed grip on the slide to feed the work forwardly, a clamp to grip the work on reverse movement of the feed grip, an operating connection from the shaft to the feed grip in controlled relation to the shaft in all positions of the slide, an operative connection from the shaft to the clamp, and means for oscillating the shaft to operate both the feed grip and the clamp.

9. In a feed of the character described, a feed slide, means for reciprocating the slide, an operating shaft parallel with the path of movement of the slide, a feed grip on the slide including a movable jaw, an operating connection from the shaft to the feed grip in controlled relation to the shaft in all positions of the slide,

10 a clamp to grip the work on reverse movement of the slide, an operative connection from the shaft to the clamp, means for operating the shaft, and said movable jaw and clamp each having surplus of motion so that operation of the shaft in one direction will first set said jaw and continued movement of the shaft will then release the clamp and on reverse movement of the shaft the clamp will first be set and on continued movement of the shaft the jaw will then be released.

15 10. In a feed of the character described, a reciprocable slide, means for reciprocating the slide, a feed grip on the slide to advance the work, a clamp to hold the work on reverse movement of the slide, an operating shaft, operative connections from the shaft to the feed grip and clamp, means for operating the shaft, a crank and a link connection from an operating means to the shaft, the connection from the operating means including an eccentric, and manually operated means for shifting the eccentric to a position that when operated it will not operate the shaft to a position to set the feed grip and clamp.

20 11. In a feed of the character described, a feed slide having a feed grip, a clamp, means for operating the slide to advance the work, an operating shaft, operative connections from the shaft to the feed grip and the clamp, an operating means, a connection from the operating means to the shaft including an eccentric, turnable from its normal operative position to another position to render the shaft ineffective to set the feed grip and clamp, and manual means for turning the eccentric.

25 12. In a device of the character described, means for gripping the work, an operating means, an operative connection from the operating means to the gripping means including an eccentric turnable to two positions in one of which it is effective to operate the gripping means and in the other of which it is ineffective to operate said means, and manual means for turning the eccentric from one position to the other to render the connection effective and ineffective to operate the gripping means.

30 13. In a device of the character described, means for gripping the work, means for operating the gripping means including a lever, means for operating the lever, an operative connection from the lever to the gripping means including a link, means pivotally connecting the link to the lever including a shaft having an eccentric, manually operable means to turn the shaft to shift the eccentric to render it ineffective to set the gripping means, and means to hold the eccentric shaft in different angular positions.

35 14. In a device of the character described, means for gripping the work, an operating means, an operative connection from the operating means to the gripping means including a shaft having an eccentric forming a pivotal connection between parts of said operative connection, a manually operable means on said shaft to turn the shaft to shift the eccentric to and from a position where it is effective to set said gripping means, means to yieldingly hold the eccentric shaft in different adjusted positions, and stop means to limit movements of the shaft when shifted to and from the operative position.
